UNITED STATES PATENT OFFICE.

SINCLAIR J. JOHNSON, OF MONTCLAIR, NEW JERSEY; SARAH JOHNSON, EXECUTRIX OF THE WILL OF SAID SINCLAIR J. JOHNSON, DECEASED, ASSIGNOR OF ONE-HALF TO WALTER C. SHULTZ, OF MONTCLAIR, NEW JERSEY.

FLUID-CLUTCH.

1,311,279.

Specification of Letters Patent. Patented July 29, 1919.

Application filed April 20, 1916. Serial No. 92,441.

To all whom it may concern:

Be it known that I, SINCLAIR J. JOHNSON, a citizen of the United States, residing in Montclair, in the county of Essex and State 5 of New Jersey, have invented new and useful Improvements in Fluid-Clutches, of which the following is a specification.

This invention relates to fluid clutches to couple and uncouple a driving element to a 10 driven element, and it is the object of the invention to provide a clutch of this character to permit of flexibility between the driving and driven elements whereby the driven element may be driven at the same 15 speed or velocity as the driving element or a reduced velocity thereto.

In carrying out the invention I provide a 20 rotatable piston adapted to be connected to a source of power and an annular fluid chamber connected to a driven element in which a piston works, and coöperates with a fluid in said chamber and an abutment or 25 abutments reciprocable transversely of the fluid chamber and the path of movement of the piston to transmit movement of the piston to the driven element, or to permit the driving element with the piston to move independent of the driven element.

In the drawing accompanying and forming 30 a part of this specification Figure 1 is a perspective view of my improved clutch.

Fig. 2 is a longitudinal sectional view.

Fig. 3 is a cross sectional view taken on 35 the line A—A of Fig. 2 looking in the direction of the arrow; and

Fig. 4 is a perspective view of the piston mechanism.

Similar characters of reference designate 40 like parts throughout the different views of the drawing.

The embodiment of my invention shown in the drawing consists of a drum or cylinder 5 having two diameters, as shown at 6 and 7, and adapted to be connected and fixed at 45 one end, as at 8, to a driven element such as a shaft or the like (not shown). The end of larger diameter is closed by a head 9 having a central opening and thereby providing an annular chamber 11 to contain a suitable 50 fluid.

A head 12 of the same diameter as the part

of the cylinder of the least diameter is journaled in suitable bearings in the cylinder head opening 10 and at the opposite end in the cylinder, as at 13, and adapted at 14 to 55 be operatively connected to a suitable source of power, said head also constituting the lower wall of the chamber 11. This head carries a radially projecting piston 15 to engage and work in the annular fluid chamber 60 11.

Abutments 17 are slidably mounted in longitudinally extending portions 16 of the cylinder, said abutments being so proportioned that their lower ends or edges will engage 65 with and are constructed to conform to the periphery of the head 12. These abutments are adapted to reciprocate transversely of the fluid chamber, and during such movement engage in grooves or guideways 18 in 70 the inner wall of the cylinder of larger diameter and constituting one of the walls of the fluid chamber, and their ends are adapted to engage in a recess 19 in the side wall of the cylinder head 9 and thereby provide a 75 fluid tight partition in the fluid chamber.

The abutments are reciprocated by the piston head 12 during the rotation thereof by a cam groove 20 in the peripheral wall of the piston head in which engage cam followers 80 21 projecting from the abutments 17. Suitable packing may be provided at the opposite ends of the piston head, as at 22 and 23.

The piston 15 is carried by the head 12 to have adjustment transversely of the head 85 and radially thereof to thereby increase or decrease the working or operating area of the piston and regulate the amount of fluid permitted to escape by the piston, and whereby to couple the driving element to the driven 90 element and uncouple it therefrom. For this purpose the piston is adjustably or slidably mounted in a transverse recess 24 in the head 12, the piston and recess being so proportioned that the piston may be adjusted to 95 be within the contour of the head 12, in which position it will not exert any force on the driven element. The piston is adjusted by gibs 25 slidably mounted within the head carrier 14 coöperating with cam slots 26 in 100 opposite sides of the piston. The gibs have laterally and oppositely extending ribs 27

- adapted to pass through slots 28 in the head carrier 14 and engage in a collar 29 slidably mounted on the head carrier 14, said collar having an annular flange 30 for the engagement of a fork of an actuating lever 32 and whereby the collar is adjusted longitudinally and with it the gibs 25. In the position shown in Fig. 2 the gibs have been adjusted to the limit of their inward movement with the piston extending radially of the head 12 to the full extent with the end flush with the inner circumferential wall of the fluid chamber 11, and it will be obvious to decrease the working area of the piston and permit the fluid to pass by the piston the collar 29 and therewith the gibs 25 will be adjusted to the left as viewed in Fig. 2, the gibs riding up in the cam slots 26 in the piston drawing the latter into the head 12.
- In operation, assuming the parts to be in the position shown in Fig. 2 with the piston adjusted outward to its full extent and with an abutment extending transversely of the fluid chamber separating said chamber and intercepting the path of movement of the piston, the pressure of the piston on the liquid on the side of the piston in which the same is being rotated will be impinged against the abutment, and as there is virtually no escape for the fluid the piston through said fluid will carry the abutment with the connected cylinder and element to be driven with it at substantially the same velocity as the piston is being rotated. Should it be desired to reduce the velocity of the driven element with relation to the velocity of the driving element the piston is adjusted into the head 12 thereby leaving a space between the end of the piston and the circumferential wall of the fluid chamber permitting the escape of a portion of the fluid in front of the piston and thereby slippage will occur between the piston and cylinder 5, with the result that the piston will be rotated faster than the cylinder or driven element. As the piston is rotated faster within the cylinder and to permit the passage of the piston past the abutment or abutments these abutments will be moved out of the path of movement of the piston and caused to intercept the same in proper timed sequence by the cam 20 in the head 12, but at all times an abutment will extend across the fluid chamber to take up the pressure of the liquid in front of the piston and thereby transmit the movement of the driving element through the piston to the cylinder and therethrough to the driven element.
- It will be readily understood that the cylinder and thereby the driven element may be driven in a reverse direction according to the direction in which the piston is rotated. It will be understood that the speed of the driven element is decreased in accordance with the passage of the fluid by the piston, and that the power of the driven element is increased by the decreasing of the working portion of the piston face which tends to increase the speed of the driving element. This condition will exist until the area of the piston is reduced and the escape of the liquid increased to such an extent that there will not be enough force exerted on the abutment to move the driven element. The clutch will not take hold suddenly but gradually, starting the driven element slowly and increasing until it is fully clutched and revolving at substantially the same velocity as the driving element. It will further be observed that as the piston is adjusted the power and speed is varied accomplishing the same object as a change of speed by gears, but an infinite number of speeds, from nothing to full clutch and full speed, is transmitted from the driving to the driven element, and that the driven element may be driven at any speed up to the full speed of the driving element.
- When the piston is adjusted outward to its full extent, as shown at 33 Fig. 2, there is a space in the piston recess in the head 12 which is in communication with the fluid chamber by a port 34. By this construction the fluid in the fluid chamber displaced by the piston when it is adjusted outward is adapted to enter into said space 33, and as the piston is adjusted into its carrier 12 the fluid is forced out of the space 33 and occupies the space which was taken up by the piston in the fluid chamber.
- Variations may be resorted to within the scope of my invention.
- Having thus described my invention, I claim:
1. A fluid clutch comprising a cylinder having an annular fluid chamber in an enlargement thereof with an abutment reciprocable transversely across said chamber and in a direction parallel with the axis of the cylinder, a piston to work in said chamber and coöperate with the abutment, and means to adjust the piston radially to increase and decrease the working area thereof, substantially as and for the purpose specified.
  2. A fluid clutch comprising a cylinder having a fluid chamber; an abutment reciprocable transversely of said chamber; and a rotatable head carrying a piston to work in said chamber and having means to reciprocate the abutment during the movement thereof and coöperate with the piston for the purpose specified.
  3. A fluid clutch comprising in combination a rotatable driving element having a piston connected thereto, a driven element including a cylinder having an annular enlargement to constitute a fluid chamber in which the piston is adapted to work, and an abutment reciprocable transversely across

the fluid chamber and the path of movement of the piston and in a direction parallel with the axis of the cylinder, substantially as and for the purpose specified.

5. 4. A fluid clutch comprising a cylinder having an annular fluid chamber; an abutment slidably carried by the cylinder to be reciprocated transversely of such chamber; a rotatable head in the cylinder adapted to reciprocate the abutment during the rotation thereof; a piston carried by the head; to work in the fluid chamber and means to increase and decrease the working area of the piston, substantially as and for the purpose specified.

5. A fluid clutch comprising a cylinder having an annular fluid chamber; an abutment slidably carried by the cylinder adapted to be reciprocated transversely of the fluid chamber; a rotatable head in the cylinder having means to reciprocate the abutment; and a piston carried by said head to work in the fluid chamber and coöperate with the abutment, substantially as and for the purpose specified.

6. A fluid clutch comprising a cylinder having an annular fluid chamber; a rotatable head in the cylinder; abutments slidably carried by the cylinder with one edge abutting against the periphery of the head and adapted to be reciprocated transversely of the fluid chamber; a piston carried by the head to work in the fluid chamber; and a cam groove in the periphery of the head in which a cam follower projecting from the abutments is adapted to engage whereby the abutments are reciprocated transversely of the fluid chamber and the path of movement of the piston in proper time sequence with the movement of the piston, substantially as and for the purpose specified.

7. A fluid clutch comprising an annular fluid chamber, a rotatable head carrying a piston to work in said chamber, and an abutment adapted to be reciprocated transversely of the fluid chamber and the path of movement of the piston alternately and in proper timed sequence with the movement of the piston, substantially as and for the purpose specified.

8. A fluid clutch comprising a cylinder having an annular enlargement to constitute a fluid chamber, a head rotatable in the cylinder carrying a piston to extend radially therefrom and to work in said chamber, and an abutment reciprocable in a direction parallel with the axis of the cylinder by the head during the rotation thereof to alternately intercept the path of movement of the piston in proper timed sequence with the movement of the piston, substantially as and for the purpose specified.

9. A fluid clutch comprising a cylinder having an annular fluid chamber; a rotatable head in said cylinder; a piston carried

by said head to work in the fluid chamber; a plurality of slidably mounted abutments carried by the cylinder with one edge abutting against the periphery of the head; and a cam groove in the periphery of the head in which cam followers projecting from the abutments engage whereby as the piston is rotated by the head the abutments will be reciprocated transversely of the fluid chamber to intercept the path of movement of the piston alternately and in proper timed sequence with the movement of the piston, substantially as and for the purpose specified.

10. In a fluid clutch a cylinder having an annular fluid chamber; a rotatable head in the cylinder; an abutment slidably carried by the cylinder with one edge abutting against the periphery of the head and adapted to be reciprocated transversely of the fluid chamber; and a piston to work in the fluid chamber carried by the head to have radial adjustment whereby to increase and decrease the working area of the piston, substantially as and for the purpose specified.

11. In a fluid clutch a cylinder having an annular fluid chamber; a rotatable head in the cylinder; an abutment slidably carried by the cylinder with one edge abutting against the periphery of the head and adapted to be reciprocated transversely of the fluid chamber; a piston to work in the fluid chamber adjustably carried by the head to extend radially therefrom; and means to adjust the piston radially of the head to increase and decrease the working area of the piston, substantially as and for the purpose specified.

12. In a fluid clutch, a cylinder having an annular fluid chamber; a rotatable head in the cylinder; an abutment slidably carried by the cylinder with one edge abutting against the periphery of the head and adapted to be reciprocated transversely of the fluid chamber; a piston to work in the fluid chamber adjustably carried by the head to extend radially therefrom; and means to adjust the piston radially of the head to increase and decrease the working area of the piston, comprising gibs slidably carried within the head engaging in diagonal slots in the piston; and means connected to said gibs to adjust them longitudinally of the head, substantially as and for the purpose specified.

13. In a fluid clutch, the combination of a fluid chamber, a rotatable piston to work in said chamber, an abutment reciprocable transversely of said chamber, and means to adjust the piston radially to increase and decrease the working area thereof and to permit the escape of liquid over the piston from in front thereof, substantially as and for the purpose specified.

14. In a fluid clutch, the combination of a fluid chamber, a rotatable piston to work in the fluid chamber, an abutment to intercept the path of movement of the piston in the fluid chamber, means to adjust the piston radially to increase and decrease the working area of the piston and permit the escape of the liquid over the piston from in front thereof, and means to move the abutment out of the path of the piston during the rotation thereof, substantially as and for the purpose specified.

10
